UNITED STATES PATENT OFFICE.

ARTHUR WILLIAMS, OF GRAND RAPIDS, MICHIGAN, ASSIGNOR, BY MESNE ASSIGNMENTS, TO COVELL-HANCHETT CO., OF BIG RAPIDS, MICHIGAN, A CORPORATION OF MICHIGAN.

POWER-TRANSMISSION MECHANISM.

Application filed February 24, 1925. Serial No. 11,017.

This invention relates to power transmission mechanism particularly adapted to actuate a cross feed for grinding machines. In machines of this character a table for carrying the work to be acted upon by an over-head grinding wheel is movable back and forth under the wheel and it is also necessary that the work be fed in a direction transverse of the movement of the table. 5 My invention is directed to novel power transmission mechanism for effecting this cross feed in either direction and also for rendering the cross feed inoperative while the machine is working, in which case the reciprocating table will move back and forth under the grinding wheel but there will be no movement of the same transverse to the direction of its reciprocatory movement. 10 My invention is directed to novel power transmission mechanism for effecting this cross feed in either direction and also for rendering the cross feed inoperative while the machine is working, in which case the reciprocating table will move back and forth under the grinding wheel but there will be no movement of the same transverse to the direction of its reciprocatory movement. 15

The invention consists in various novel mechanisms for attaining the above described ends all of which will fully appear as understanding of the invention is had from the following description taken in connection with the accompanying drawings, in 20 which:

Fig. 1 is a partial end elevation and vertical section of the upper portion of a grinding machine equipped with the invention.

Fig. 2 is a vertical section on the plane of line 2—2 of Fig. 3, and

Fig. 3 is an enlarged vertical section through the novel form of clutch mechanism used to control the cross feed.

Like reference characters refer to like parts in the different figures of the drawings.

The grinding machine includes a suitable supporting pedestal or body 1 from which, at the rear, a vertical support 2 extends on which a forwardly extending arm 3 is mounted, the same carrying the grinding wheel 4 at its front end. The details of mechanism for rotatably mounting and driving the grinding wheel at high speed form no part of this invention and are not disclosed. At the upper side of the body 1 a cross table 5 is mounted, on the under side of which are V-shaped guides 6 slidably

mounted in suitable grooves in the top of the body 1 so that the table may be moved to the rear or forwardly as is evident. 50 Above the cross table 5, a work holding table 7 is mounted for movement back and forth under the grinding wheel, the work holding table being equipped with a suitable V-shaped guide 8 to direct the same on the cross table 5. In practice this work holding table is reciprocable so that the work carried thereon is moved back and forth and may be acted upon by the grinding wheel 60 above it.

From the cross table 5 a lug 9 extends downwardly through a slot 9^a in the top of the body 1 of the grinding machine. A shaft 10, screw threaded at its inner end, 65 passes through the lug and at its outer end is equipped with a crank or handle 11 so that it can be manually turned, the shaft at its front end passing through and being rotatably supported in the down-turned 70 apron 12 integrally formed with the top of the body 1 and spaced a distance in front of the front side 1^a of the body as shown in Fig. 1. By turning the crank or handle 11 it is evident that the cross table carrying the 75 work holding table may be moved inwardly or outwardly so as to bring the work in proper position with respect to the grinding wheel. This is necessary, particularly when work is first attached to the work holding table and it is desired to move the 80 same to proper position for the beginning of the action of the grinding wheel on the work.

A pinion 13 is fixed to the shaft 10 and 85 meshes with a gear 14 formed on a relatively large cup-shaped housing 15. The bottom of this housing has a central opening through it through which a heavy cylindrical driving member 16 extends, which is formed at the 90 upper end of an arm 17, the same bearing against the outer side of the base of the housing 15 and being located between said housing and a large boss 12^a integral with and extending inwardly from the apron 12. 95 A shouldered stud 18 passes through the

apron and the boss 12^a and is threaded into the member 16 whereby said member 16 is rotatably mounted to turn about the axis of the stud 18, said stud turning freely in the 5 boss 12^a.

The open side of the housing is closed by a ring or plate 15^a and attached thereto by screws 15^b and a large central opening is made through it for the passage of a cup-shaped shifting member 19 having a closed outer end 19^a. This member at its inner side is formed with a suitable keyway 20^a in which a key 20 secured to a sleeve 21 surrounding the member 16 is located, the 10 sleeve 21 being permanently secured to the member 16 by means of the dowels 22, best shown in Fig. 3. Sleeve 21 is also formed with a number of longitudinal slots 23 in its outer side in which spring actuated fingers 15 24 passing through radial openings in the member 19 may at times be partly received, the springs actuating said fingers 24 being seated against the bottoms of the slots 23.

Located within the housing 15 and around the member 19 are three rings 25, 26, and 27. The ring 25 is located between rings 26 and 27 and formed at its inner side with a concave annular recess into which the projecting convex outer ends of the fingers 24 may be received. Rings 26 and 27 are each formed at their inner curved sides with a plurality of spaced apart slots or grooves 28 in which the projecting ends of the fingers 24 may be received on longitudinal movement of the shifting member 19, being received in the slots 28 of the ring 27 when moved in one direction and in the slots 28 of the ring 26 when moved in the opposite direction. Each of the rings 26 and 27 at 40 its outer curved side is formed with a consecutive series of ratchet teeth 29. The rings 25, 26 and 27 are surrounded by a larger ring 30 having a width equal to the combined width of the three rings 25, 26 and 27. The ring 25 is contained within the ring 30 and may be either fixed or rotative relative thereto, its operation not being affected by rotation. This ring 30 is located within and permanently secured in fixed 45 position to the sides of the housing 15 by use of dowels 30^a similar to the dowels 22 previously noted. At a number of points in the circumference of the outer ring 30 around each of the inner rings 26 and 27, slots are cut in which spring actuated blocks 50 31 are slidably mounted, each at its inner end being formed with a dog 32 shaped to fit between any two consecutive teeth 29 of the associated rings 26 or 27. It is evident that 55 with the dogs engaged with the ring 26, for example, on movement of said ring in one direction, the housing 15 will be rotated but when moved in the opposite direction the ratchet teeth will slip over the dogs 32 and 60 the housing will not be turned. The teeth 65

29 on the two rings 26 and 27 are oppositely formed and the dogs 32 to engage therewith correspond, whereby by connecting the inner member 16 with one of the rings, an oscillation of the housing 15 will take place 70 in one direction with no movement in the opposite direction, while the connection with the other ring will cause a directly reverse movement of the housing 15 with no movement in the other direction; and with the 75 shifting member 19 in a neutral position, as shown in Fig. 3, the turning of the inner driving member 16 has no effect upon the housing 15.

A rod 33 passes through the upper end 80 of the front 1^a of the body 1 and is permanently connected to the base 19^a of the shifting member. At its inner end it passes through a sleeve 34 in which it may rotate, said sleeve being held against longitudinal movement on the rod between a collar 35 pinned to the rod at one end of the sleeve 34 and the head 33^a formed at the inner end of the rod 33. Sleeve 34 is located between two arms of the yoke 36 at the end of a 90 short bar 37 which is pivotally connected to the upper end of an arm 38, fixed to the horizontal rock shaft 39 mounted on the body of the grinding machine and extending outwardly at one end beyond the side of 95 said body where it is equipped with a suitable handle for manual operation. The arms of the yoke 36 are pivotally connected to the sleeve 34 at opposite sides as shown in Fig. 3. It is evident that by manual 100 operation of the handle the shifting member 19 may be moved to any one of its three positions, the neutral position as shown in Fig. 3, or to connect the fingers 24 with either 105 of the rings 26 or 27.

A link 41 is pivotally connected at its upper end to the end of the arm 17 and at its lower end to a disk 42. An adjustable connection is made with the disk 42 by means of a releasable connection 43 which may be shifted to different positions in a radial slot (not shown) cut in the disk 42. This disk 42 in grinding machines of this character is driven, by means not disclosed, so as to turn in one direction and then reverse its 110 turning movement whereby, through the connection made by link 41 with the arm 17, the member 16 extending into the housing 15 is oscillated. This oscillation takes place at the end of a reciprocating movement of the 120 work holding table. Inasmuch as the mechanism for driving the disk 42 is old, common and well known in machines of this character and forms no part of the present invention, it is not shown or described.

With the construction described the cross feed or the cross table 5 may be controlled as desired. By operating the handle connected to the shaft 39 in one direction and thereby connecting the member 16, which 130

oscillates back and forth about its axis and serves as a driving member, with one of the rings 26 or 27 a rotation of the housing 15 and the gear 14 thereon in one direction is had, this turning the shaft 10 and moving the cross table 5 in one direction; but by connecting said driving member 16 with the opposite ring the rotation of the housing 15 is in the opposite direction and the cross table is moved in the opposite direction. Accordingly movement in or out automatically effected by the mechanism described may be had. And when it is desired that the cross table have no movement, a neutral position is provided wherein the driving member 16 does not engage with either ring 26 or 27, this neutral position being shown in Fig. 3. The construction is very practical and effective and has so proved in practice. Various changes in detail may be resorted to without departing from the invention defined in the appended claims and it is to be considered that the invention is comprehensive of all forms of structure coming within the scope of said claims.

I claim:

1. Transmission mechanism comprising a cup-shaped housing, a driving member mounted for oscillation about a horizontal axis extending into said housing, a shifting member slidably keyed on said driving member and extending thereover, two separate means located within the housing, with either of which said shifting member may be selectively connected so that either of said means may be driven back and forth by the oscillation of the driving member, and means interposed between each of said separate means and the housing for driving the housing when said means is turned in one direction and not drive the housing when turned in the opposite direction, the direction of driving of the housing by said means being opposite with the two means, substantially as described.

2. A construction containing the elements in combination defined in claim 1 combined with an intermediate means interposed between said two means with which the shifting member may be engaged, said intermediate means being free from connection to the housing whereby the housing may remain at rest while the driving member is oscillated, substantially as described.

3. Transmission mechanism comprising a housing mounted for rotation, a driving member extending into the housing adapted to be oscillated back and forth about its axis, a shifting member keyed to said driving member and shiftable lengthwise thereof, two spaced apart rings mounted within the housing and formed at their outer curved sides with consecutive ratchet teeth and at their inner curved sides with spaced apart slots, the ratchet teeth of the two rings be-

ing oppositely cut, means carried on the shifting member adapted to selectively pass into slots in said rings to thereby connect the rings with the driving member, and spring actuated dogs carried by the housing engaging with the ratchet teeth, said dogs on rotation of a ring in one direction connecting the housing therewith whereby it is rotated and in the opposite direction slipping over the teeth of the ratchet, substantially as described.

4. A construction containing the elements in combination defined in claim 3 combined with a third ring located between said ratchet rings, said third ring being free from connection with the housing and at its inner side being formed to engage with said means carried by the shifting member, substantially as and for the purposes described.

5. Transmission mechanism comprising a rotatable housing, a driving member extending into the housing at one side adapted to be oscillated back and forth about its axis, a shifting member keyed to the driving member and extending into the housing from the opposite side, two separate members located within the housing with either of which the shifting member may be selectively connected, interengaging means between one of said members and the housing for driving the housing in one direction on oscillation of said member in said direction, said means being inoperative to drive the housing in the opposite direction on the oscillation of said member in said opposite direction, and like interengaging means between the housing and the other member whereby the housing is driven in the direction opposite to which it is driven by the first member, substantially as described.

6. A construction of the class described, comprising a cup-shaped housing, a driving member extending into one side of the housing, said driving member being adapted to be oscillated back and forth about its longitudinal axis, a shifting member extending into the opposite side of the housing and over the driving member, said shifting and driving members being splined together, two spaced apart rings located in the housing around the shifting member, each of said rings at its inner curved side being provided with a plurality of spaced apart transverse slots, spring actuated keys carried by the shifting member adapted to be received in said slots, ratchet teeth at the outer curved side of each of said rings, the teeth of one of the rings being cut opposite to the teeth of the other, spring actuated dogs carried by the housing to engage with said teeth whereby the housing is driven by a ring connected with the shifting member in one direction when the ring is turned in said direction and is not driven when the ring is turned in the opposite direction, the direction of driving

105

110

115

120

125

130

for the two rings being opposite, and means for slidably moving the shifting member in the direction of its longitudinal axis, substantially as described.

5. 7. A construction containing the elements in combination defined in claim 6 combined with a third ring between the two ratchet

rings, said third ring being loosely mounted within the housing and formed at its inner side with an annular recess shaped in conformity with the outer ends of said keys, substantially as described. ¹⁰

In testimony whereof I affix my signature.

ARTHUR WILLIAMS.
